(57) **CLAIM**

The ornamental design for a combined bottle and bottle holder, as shown and described.

DESCRIPTION

FIG. 1 is a front elevational view of a combined bottle and bottle holder of my new design;

FIG. 2 is a top plan view thereof;

FIG. 3 is a sectional view taken along the line 3—3 of FIG. 1;

FIG. 4 is a rear elevational view thereof;

FIG. 5 is a bottom plan view thereof;

FIG. 6 is a side elevational view of the left side thereof;

FIG. 7 is a side elevational view of the right side thereof;

FIG. 8 is a perspective view of the bottle holder of FIG. 1;

FIG. 9 is a front elevational view of FIG. 8;

FIG. 10 is a rear elevational view of FIG. 8;

FIG. 11 is a top plan view of FIG. 8;

FIG. 12 is a side elevational view of the left side of FIG. 8;

FIG. 13 is a side elevational view of the right side of FIG. 8;

FIG. 14 is a bottom plan view of FIG. 8; and,

FIG. 15 is a sectional view taken along line 15—15- of FIG. 11.
